CLAIM

The ornamental design for an architectural panel, as shown and described.

DESCRIPTION

FIG. 1 is a bottom, front, right perspective view of an architectural panel according to a first embodiment of our new design;

FIG. 2 is a top, front, right perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof;

FIG. 8 is a top plan view thereof;

FIG. 9 is a bottom, front, right perspective view of an architectural panel according to a second embodiment of our new design;

FIG. 10 is a top, front, right perspective view thereof;

FIG. 11 is a front elevation view thereof;

FIG. 12 is a right side elevation view thereof;

FIG. 13 is a rear elevation view thereof;

FIG. 14 is a left side elevation view thereof;

FIG. 15 is a bottom plan view thereof;

FIG. 16 is a top plan view thereof;

FIG. 17 is a bottom, front, right perspective view of an architectural panel according to a third embodiment of our new design;

FIG. 18 is a top, front, right perspective view thereof;

FIG. 19 is a front elevation view thereof;

FIG. 20 is a right side elevation view thereof;

FIG. 21 is a rear elevation view thereof;

FIG. 22 is a left side elevation view thereof;

FIG. 23 is a bottom plan view thereof; and,

FIG. 24 is a top plan view thereof.

The broken lines illustrating portions of the architectural panel form no part of the claimed design. The dot-dash broken lines define the bounds of the claimed design and form no part thereof.

1 Claim, 15 Drawing Sheets
